J. R. WEISIGER, OF DANVILLE, KENTUCKY.

Letters Patent No. 61,492, dated January 22, 1867.

IMPROVEMENT IN PUMPS.

The Schedule referred to in these Letters Patent and making part of the same.

TO ALL WHOM IT MAY CONCERN:

Be it known that I, J. R. WEISIGER, of Danville, in the county of Boyle, and State of Kentucky, have invented a new and useful Improvement in "Pumps;" and I do hereby declare that the following is a full, clear, and exact description thereof, which will enable others skilled in the art to make and use the same, reference being had to the accompanying drawings, forming part of this specification.

The present invention consists in so constructing and arranging the various parts composing the pump as to secure a continuous suction, while at the same time the oil or other liquid in which the pump is working is being lifted and thrown out or discharged from the pump in a continuous stream. In accompanying plate of drawings my improvement in pumps is illustrated, the—

Figure 1 being a central vertical section of the same; and

Figure 2 a similar section, but of an addition thereto.

A, in the drawings, represents the pump-cylinder or tube, in which is arranged, so as to move air-tight, a piston, B, having a rod, C, attached to it, that plays in and through the centre of a disk, or plate, D, secured across the inside of the cylinder or tube A, at or near its upper end; the aperture through this plate, D, being suitably packed to form an air-tight joint with the piston-rod. In the cylinder A, at or near its lower end, a ball or other suitable valve, G, is placed, opening upwards, which valve is below the piston B. Below the valve G a pipe or tube, H, communicates with the pump-tube or cylinder A, which pipe extending upward upon the outside of the cylinder A, again communicates with the same at a point a little below its partition plate D, and above the piston-head. In the pipe or tube H, at or near its lower end, or near the point where it communicates with the cylinder A below the valve G, a ball or other suitable valve, I, is placed so as to open upwards. J, another tube communicating at its lower end with the cylinder A, at a point just above its valve, G. This tube, J, extends upward outside of the cylinder A, and at its upper end again communicates with the said cylinder A at a point above its partition-plate D. In the tube J a ball or other suitable valve, K, is arranged, at or near its lower end, which valve opens upwards. L, a short tube or pipe communicating at its lower end with the cylinder A just below its partition-plate, D, and at its upper end with the said cylinder above the said plate D; this tube extending upward and outside of the cylinder A, and being provided with a valve, M, at or near its lower end, opening upward. N, the discharge spout or nozzle of the cylinder A, communicating with the same above the partition-plate D.

From the above description of the construction and arrangement of the various parts composing the pump, together with the drawing accompanying the same, it is plain to be seen that by the up-and-down movement of the piston in the cylinder, or tube A, a continuous suction of the oil or other liquid, in connection with which the pump is arranged to operate, must take place, while at the same time the liquid is being lifted or raised and discharged from the pump in a continuous stream. In fig. 2 the addition shown consists in arranging an air-chamber in the pump-cylinder or barrel A, and in such a manner that it can be thrown into connection with or disconnected from the said barrel according as it is desired to use the same or not, for facilitating the operation of the pump; this air-chamber, O, being formed by enlarging the pump-barrel, and put into or out of connection with the pump-barrel, through a concentric tube or cylinder, P, provided with a screw-thread around its outside, and a collar, Q; the air-chamber being shown in connection with the pump-barrel in fig. 2, but being disconnected when the lower end of the screw-tube P is screwed into the screw-socket R of the pump-barrel, as is apparent.

I claim as new, and desire to secure by Letters Patent—

The pump-cylinder or tube A, provided with a piston, B, partition-plate D and valve G, in combination with the tubes H J L, having valves I, K, M, respectively, when all arranged with regard to each other so as to operate substantially in the manner and for the purpose described.

J. R. WEISIGER.
